[57] CLAIM

The ornamental design for a clip connector for windscreen extensions or the like, substantially as shown.

DESCRIPTION

FIG. 1 is a top plan view of a clip connector for windscreen extensions or the like showing my new design;
FIG. 2 is a left side elevation thereof, the right side
being a mirror image;

FIG. 3 is a bottom plan view thereof;

FIG. 4 is a front elevation thereof; and,

FIG. 5 is a rear elevation thereof.
